UNITED STATES PATENT OFFICE.

JOHN C. HIGDON, OF KANSAS CITY, MISSOURI.

AUTOMATIC STOVE-DAMPER.

SPECIFICATION forming part of Letters Patent No. 283,106, dated August 14, 1883.

Application filed January 24, 1883. (No model.)

To all whom it may concern:

Be it known that I, JOHN C. HIGDON, of Kansas City, Jackson county, Missouri, have invented a new and Improved Automatic Stove-Damper, of which the following is a full, clear, and exact description.

The object of my invention is to improve that class of dampers which are automatically graduated in the opening which they leave for the escape of the products of combustion by the draft itself.

Reference is to be had to the accompanying drawings, forming part of this specification, in which similar letters of reference indicate corresponding parts in both figures.

Figure 1 is a sectional elevation of a smoke-pipe with my improved automatic damper applied to it, and Fig. 2 is a plan view of the upper portion of Fig. 1 inverted.

20 In any suitable chamber, *a*, of larger dimensions than the smoke-pipe and fitted in it in any approved way, or attached to the stove or furnace directly, I propose to arrange a damper, *b*, on a lever, *c*, pivoted at *d* or other suitable place, and having a weight, *e*, nearly balancing the damper, so that when the ascending currents become strong by rapid combustion said damper will be lifted by them and closed against the base *f* of the outlet *g*.
25 The weight is adjustable along the lever to be shifted, when required.

To prevent the damper from falling too low I construct the chamber-case with a stud, *h*, on

which the damper may rest when it has fallen sufficiently low. To allow the smoke to escape 35 when the damper is closed, I make a hole, *i*, through it, and provide another damper, *j*, for it, that may be set from time to time to regulate the size of the passage, as required.

The chamber may be constructed in any approved way; but I prefer to make it to consist of the bowl-shaped castings *k*, with flange *l* and pipe-collars *m*, said parts being bolted together by the flanges, and one having a suitable opening, *n*, through the side for the lever *c*.
40

I am aware that a counterpoised damper is not new; also, that a damper has been made in two sections correspondingly apertured and sliding one upon the other, so that their apertures will register more or less; but 50

What I claim as new and of my invention is—

1. An automatic stove-damper supported, for a maximum draft, upon a vertical projection, *h*, rising from the chamber *k*, as shown and described.
55

2. The combination, with the smoke-flue of a stove or furnace, of a damper, *b*, arranged to be raised and closed by the escaping products 60 of combustion, and having a smoke-passage, *i*, and a damper, *j*, substantially as described.

JOHN C. HIGDON.
